(57) **CLAIM**

The ornamental design for an applicator assembly, as shown and described.

DESCRIPTION

FIG. 1 is a perspective front view of an applicator assembly embodying the new design shown;
FIG. 2 is a top view of the design shown in FIG. 1;
FIG. 3 is a bottom view of the design shown in FIG. 1;
FIG. 4 is a left side view of the design shown in FIG. 1;
FIG. 5 is a right side view of the design shown in FIG. 1;
FIG. 6 is a front view of the design shown in FIG. 1; and,
FIG. 7 is a back view of the design shown in FIG. 1.
Broken lines shown in the figures described above are for illustrative purposes only and form no part of the claimed design.
